United States Patent Office

Des. 204,042
Patented Mar. 8, 1966

204,042

DISPLAY STAND

Marguerite C. Stix, 13 Vandam St.,
New York, N.Y.

Filed June 17, 1965, Ser. No. 85,784

Term of patent 14 years

(Cl. D80—9)

FIG.3

The broken line representation of a sea shell in FIG. 1 is for purposes of illustration only.

I claim:

The ornamental design for a display stand, as shown and described.
